ALBERT GEORG KOECHLIN, OF BASEL, SWITZERLAND, ASSIGNOR TO SPINNEREI & WEBEREI STEINEN ACTIEN-GESELLSCHAFT, OF STEINEN, GERMANY.

WEFT-BOBBIN-EXCHANGE DEVICE FOR LOOMS.

1,142,569.

Specification of Letters Patent. Patented June 8, 1915.

Application filed June 27, 1914. Serial No. 847,610.

To all whom it may concern:

Be it known that I, ALBERT GEORG KOECHLIN, a citizen of the Swiss Republic, and resident of Basel, Switzerland, have invented new and useful Improvements in Weft-Bobbin-Exchange Devices for Looms, of which the following is a full, clear, and exact specification.

In automatic weaving looms it is already known at each weft bobbin exchange to draw off and to hold fast by means of gripping fingers, the end of the weft thread wound about the point of the lowermost weft bobbin ready for being transferred into the shuttle, until the end of the thread is threaded into the shuttle. It has been found that it is possible that this thread end may not be caught by said fingers and the new weft bobbin is then struck through the shuttle downward into the lower collecting receptacle for the empty spools.

According to the present invention, the drawing off of the thread end of the weft bobbins is also effected by means of a positively moved gripping device, but is distinguished by the fact that the tongs-like gripper is arranged to engage by means of wide gripping jaws over the points of several bobbins at a time, in order to grip the thread ends of several bobbins simultaneously and to draw them off, and in all events, in the event of a failure of gripping the thread end of a bobbin, to attain this object by a second or even a third application of the gripper so that in consequence of the repeated possibility of grip, every security may be afforded for a correct gripping and drawing off of the thread ends of the bobbins. The gripping jaws are preferably provided with a lining of bristles or the like which possess sufficient adhesiveness in order to grip with certainty the thread end upon the point of the bobbin. A special advantage may further be seen in the present invention in that also the thread ends are gripped with certainty on those spools which are not placed exactly perpendicular to the direction of feeding, but lie, from whatsoever reason, sloping to the same or otherwise depart from the normal position, because, in consequence of the width of the gripping jaws, these latter are in a position to grip the thread end with certainty, even with such abnormally placed bobbins.

The accompanying drawing illustrates an example of the invention.

Figure 1 shows a side elevation, and Fig. 2 a plan view of the improved device. Fig. 3 shows a detail view of the gripping jaws. A (Fig. 2) is the inclined guide-way for the bobbins coming for example from a box-like magazine and B is the usual transfferer for introducing the lowermost bobbin into the shuttle, when a bobbin change takes place, as it is well known in apparatus of this kind.

Upon the fixed supporting block *a* there is secured upon a pivot *b* an oscillating lever *c* which is kept in the position of rest indicated in Fig. 2 in full lines by means of the action of a spring *d*. At the lower end of the lever pivot *b* is fixed an arm *e* with a point *f*, which on the commencement of the bobbin exchange operation, is brought in the well known (here therefore not specially described) manner from a normally inoperative position, in which it is turned sideward, into an operative position which is that shown in the drawings and in which it lies in the path of a stop *g* on the lay or batten so as to be thrown back by the lay when the latter swings in the direction toward the point or finger *f* and to thus cause an inward motion of the lever *c* into the position indicated in dot-and-dash lines in Fig. 2 to an extent limited by an adjustable stop *h*.

At the front end of the lever *c* is placed a tongs-like gripper formed of two spring compressed gripping jaws *g*, *h*. Of these gripping jaws, the one *g* is fixed upon the lever *c*, but the other *h* is pivoted upon it and placed under the influence of a spring *i*. On the inward oscillation of the lever *c*, the movable gripping jaw *h* slides upon the sloping piece *k* of an opener *n* pivoted at *m* and under spring pressure, which sliding movement has for its effect that the gripper is opened in order in the open position to be thrust over the bobbin points where the thread end is wound, and then allowed to close on them. Now, the width of the gripping jaws *g*, *h* is so great that these jaws thus engage over the points of three or more bobbins at once, as is shown in Fig. 2. If then the outward oscillation of the lever *c* takes place under the action of the spring *d*, then under normal conditions, the thread

ends of the three bobbins in question are drawn off by the gripper and held fast, while the movable gripping jaw *h* can slip unhindered past the opener *n*, which is now 5 pushed back and can freely yield or rock upon its pivot *m*. As may be seen in this arrangement, each bobbin comes with its thread portion thrice or more within the range of the gripper. If, therefore, for any 10 reason whatever, the thread end of the bobbin *x* should not be gripped the first time, this will take place when the bobbin *x* has moved into the position of the bobbin *y*, on the renewed inward oscillation of the lever 15 *c* between the gripping jaws, so that it can then be seized by these jaws, or if this should again miss, then certainly the third time, when the point of the bobbin which is moved into the place of the bobbin *z* is again at 20 tacked by the inwardly oscillating gripper *g*, *h*, so that the thread end of the bobbin will with certainty be caught and held fast and so forth. This repeated gripping of each bobbin gives the advantage that the 25 missing of the threading-in of the shuttle in consequence of the failure to hold fast the bobbin thread end need no longer be feared, which otherwise may take place when the spool is gripped only once.

30 The gripping jaws *g*, *h* of the gripper are preferably provided with a lining of bristles in the manner best shown in Fig. 3; they might however be provided with any other suitable lining possessing sufficient adhesion 25 to grip with certainty the thread end at the point of the bobbin.

What I claim is:

1. In weft bobbin exchange devices for looms of the kind described, a guide-way for

feeding the bobbins, a transerrer for inserting the bobbins one by one into the shuttle, a movable thread end drawing-off gripper having operative jaws relatively movable to one another, means for moving said gripper onto the bobbin points, means 4 for opening and closing the gripper jaws so as to allow them to take over the thread end wound on the bobbin points and to grip it, and means for returning the gripper to its position of rest, the gripper jaws 5 having such a form as to simultaneously grip the thread ends of several bobbins, substantially as and for the purpose described.

2. In weft bobbin exchange devices for looms of the kind described, a guide-way 5 for feeding the bobbins, a transerrer for inserting the bobbins one by one into the shuttle, a movable thread end drawing-off gripper having operative jaws relatively 6 movable to one another, means for moving said gripper onto the bobbin points, a yieldingly supported sloping piece for opening and closing the gripper jaws so as to allow them to take over the thread end wound on the bobbin points and to grip it, and means 61 for returning the gripper to its position of rest, the gripper jaws having such a form as to simultaneously grip the thread ends of several bobbins, substantially as and for the purpose described.

In witness whereof I have hereunto signed my name this 16th day of June 1914, in the presence of two subscribing witnesses.

ALBERT GEORG KOECHLIN.
